(57) CLAIM

The ornamental design for a handle, as shown and described.

DESCRIPTION

FIG. 1 is a front perspective view of a handle showing our new design;

FIG. 2 is a front elevational view thereof;

FIG. 3 is a rear elevational view thereof;

FIG. 4 is a left side elevational view thereof; the right side being a mirror image thereof; and,

FIG. 5 is a top plan view thereof.

The broken lines in the Figures are illustrative purposes only and form no part of the claimed design.
